Dutee Arnold of Providence, R. I.
Letters Patent No. 487 Dated Aug 17th 1852

Dec. 487

The schedule referred to in these Letters Patent and making part of the same

To all Persons to whom these Presents shall come:

Be it known that I, Dutee Arnold of Providence in the County of Providence and State of Rhode Island have produced a new & original design for a parlor stove and I hereby declare that the said new design is fully described & represented in the following specification and accompanying drawings to which reference is hereinafter made.

The Figures of the accompanying plates of drawings represent my new design. In Plate 1, Fig 1. is a front elevation of the stove and fig. 2. is a section of the front plate, taken in the plane of the line A B. In Plate 2 fig 3 is an end elevation of the stove and fig 4 is an elevation of the opposite end. In plate 3, fig. 5 is a plan or top view.

The bottom plate and whole base of the stove are ornamented with the lead work a. a. a, and the legs with the scroll & leaf work b. b. The fire chamber door is composed of the mouldings c. c. and lattice work d. d.

Under this door is the panel e. e. on which

are raised figures of children f,f with a fawn g & tree h. On the top of the stove is placed the vase i,i, ornamented with points or spear heads k,k, the cover being formed of the leaf work l,l.

The end plate m,m has on it the figure of a woman o,o with foliage oo in the back ground. Above this is the window or lattice d,d.

The opposite end plate p,p, is ornamented with the window or lattice d,d, and the figure of a man q,q, with foliage rr.

The top plate is ornamented with bead work a,a.

Having thus described my new design I shall state my claim as follows:—

What I claim as my production & desire to have secured to me by Letters Patent is, the new design consisting of the bead and lattice work & human figures herein above described and represented in the drawings, for a parlor stove.
